[57] **CLAIM**

The ornamental design for a combined napkin, salt and pepper container holder, as shown and described.

DESCRIPTION

FIG. 1 is a perspective view of a combined napkin, salt and container holder showing my new design, with the broken lines showing matter for illustrative purposes only and forming no part of the claimed design;

FIG. 2 is a front elevational view of the combined napkin, salt and pepper container holder;

FIG. 3 is a rear elevational view of the combined napkin, salt and pepper container holder;

FIG. 4 is a left side elevational view of the combined napkin, salt and pepper container holder, with the right side elevational view being a mirror image thereof, and with the broken lines showing matter for illustrative purposes only and forming no part of the claimed design;

FIG. 5 is a top plan view of the combined napkin, salt and pepper container holder; and,

FIG. 6 is a bottom plan view of the combined napkin, salt and pepper container holder.

FIGS. 2–6 are shown on a reduced scale.
